GRINDING MILL

Maxwell L. Rahner, Highland Park, Ill.

Application February 16, 1939; Serial No. 256,679

6 Claims.

(Cl. 83—9)

This invention relates to grinding mills and more particularly to improved linings therefor, although certain features thereof may be employed with equal advantage for other purposes.

It contemplates more especially the provision of improved liners for grinding mills effecting its function through motion and agitation of balls, tubes, rods, and similar devices with minimum wear upon the liners and the enclosing protective shell thereof.

Numerous types of grinding mill liners have heretofore been proposed and for the most part these are formed from cast material or specially rolled plates having anchoring expedients connected to interposed lifting members. Specially rolled plates are expensive and it is not entirely desirable to secure such in position through the lifting elements. The use of standard lifting elements such as rails and of standard shapes of steel plates provides a less expensive and more efficient grinding mill liner. This is especially true in that it is customary in this art to provide renewable lining sections to replace worn parts thereof, and the adaption of standard elements such as rails and steel plates substantially eliminates the initial and replacement cost.

Then, too, the provision of liner plates as a retaining expedient for the lifting elements disposed therebetween is, so far as presently known, an advantageous departure from known parts. This affords the replacement of worn lifting members by merely loosening the intermediary plates, and their replacement is effected with minimum expense and time requirements.

One object of the present invention is to simplify the construction and improve the operation of devices of the character mentioned.

Another object of the present invention is to provide grinding mill liners of standard shapes of plates and intermediary lifting elements to minimize the initial and replacement cost thereof.

Still another object is to provide grinding mill liners and standard shapes of plates and intermediary lifting elements and having the former as a securing member for the latter.

A further object is to provide a grinding mill liner consisting of standard steel plates and rails serving as lifting elements therefor with the shell anchoring expedients connected to intermediate plates to retain the lifting elements in operative position.

A still further object is to provide improved flat or curved rectangular rolled steel plates that operatively cooperate with lifting members to serve as an anchoring expedient therefor.

Still a further object is to provide an improved liner plates consisting of a combined sheet and lifting element that are complementary to each other for peening engagement responsive to

fasteners connected therebetween and somewhat offset from the center of the liner plates to accomplish effective peening interengagement.

Other objects and advantages will appear from the following description of an illustrative embodiment of the present invention.

In the drawings:

Figure 1 is a sectional view in elevation taken through a grinding mill illustrating liner plates and lifting elements embodying features of the present invention.

Figure 2 is a perspective view of a liner plate of the type shown in Figure 1.

Figure 3 is an enlarged fragmentary sectional perspective view of the grinding mill shown in Figure 1.

Figure 4 is a fragmentary perspective view of a modified grinding liner consisting of integral plates and lifting elements with the anchoring means disposed therebetween.

Figure 5 is a fragmentary perspective sectional view of a still further modified form of liner plates and intermediary lifting elements.

Figure 6 is a perspective view of a somewhat curved rectangular liner plate of the type shown in Figure 5.

Figure 7 is a fragmentary perspective sectional view of the modified lifting element shown in Figure 5.

Figure 8 is a fragmentary perspective sectional view of flat rectangular liner plates with a still further modified form of lifting element disposed therebetween.

Figure 9 is a fragmentary perspective sectional view of curved rectangular lining plates combined with modified lifting elements that are in circumferential alignment therewith.

The structure selected for illustration comprises a substantially cylindrical shell 10 of a conventional grinding mill. The shell 10, in this instance, has its interior lined with a plurality of detachably associated flat steel rectangular plates 11. The substantially flat rectangular plates 11 extend for any desired length and width, and merely comprise a component part of the sectional liner that extends longitudinally for the length of the grinding mill shell 10. To this end, substantially flat liner plates 11 extend longitudinally of each other so that their ends 12—13 are in adjacent contact (Figure 3) and the number depend upon the requirements of handling and the length of the particular grinding mill shell 10 together with the most efficient unit size thereof.

A plurality of frusto-conical apertures 14 and 15, in this instance two, are provided along a longitudinal median line of each plate 11 to receive anchoring fasteners such as threaded bolts 16 having correspondingly shaped and sized heads 17. The frusto-conical heads 17 of the threaded

fasteners 16 are preferably provided with a correspondingly sized nib 18 to cooperate with properly sized grooves 20 provided in the inclined surfaces of the apertures 14-15. In consequence thereof, the shanks of the fasteners 16 will not turn as their nuts 21 are turned down tight against the shell 10 with the fastener shank 16 projecting through suitable apertures 22 therein.

The width of the plates and the number thereof that are circumferentially spaced around the internal periphery of the shell depends upon the diameter thereof and the size of the lifting elements 23 disposed therebetween. The lifting elements 23 preferably though not essentially consist of standard rails having side channels 24 and 25 that define the rail head 26 and a substantially wider base flange 27, a cross section thereof being of standard and conventional design with the channels 24-25 serving to receive the side edges 28 and 29 of the liner plates 11 disposed therebetween to define a continuous liner comprising the plates 11 and the intermediary lifting elements 23.

Turning the nuts 21 down tight exteriorly of the shell 10 will serve to retain the lifting elements 23 in a predetermined assembled relation therewith for turning with the shell 10. With this arrangement, the lifting elements 23 are secured indirectly by the liner plates 11, and this affords the convenient replacement of either or both elements 11-23 comprising the internal liner of the shell 10. It should be observed that the lower longitudinal corners 30 and 31 of the liner plates 11 will engage the base 27 so as to effectively grip the steel therebetween to avoid the minutely ground materials confined interiorly of the liners 11-23 to find their way to the shell 10, thereby avoiding appreciable wear and injury thereto over long periods of operating use.

It is to be noted that the lifting elements 23 such as the rails 26 can be composed of a single length or a plurality of lengths can be disposed in alignment so that their adjacent contacting edges 32 and 33 have joined contact to alternate with the adjacent engaging edges 12-13 of the liner plates 11 (Figure 3). It will be apparent, therefore, that the inner liner plates 11 with their retaining elements 23 are composed of standard shapes now available on the market, and these structural elements provide an effective liner 11 with intermediary lifting elements 23 with comparatively small initial and replacement cost.

In the modified embodiment shown in Figure 4, the liner plates 11' are formed integral with the lifting members 23' to define a wave-like or sinusoidal liner configuration. The lifting elements 23' are alternately disposed to define complementary lifting element segments 24'-25' presenting depending and upstanding flat inclined engaging surfaces 28' and 29'. The bias or angle of the inclined surfaces 28'-29' is sufficient to effect a peening action when engaged by the complementary lifting element segments 24'-25' of the next adjacent liner plate 11' to enable sealing engagement therebetween responsive to threaded fastener bolts 16' that extend therethrough for engagement by fastener nuts 21' in threaded engagement therewith on the exterior side of the shell 10'.

It is to be noted that the formation of the plate 11' with its oppositely disposed complementary lifting element segments 24'-25', is such that the bottom surfaces 34 of the intermediary trough will be somewhat spaced from the inner surface

of the shell 10' when the inclined contacting surfaces 28'-29' are in engagement. Consequently, when the fastener nuts 21' are drawn down tightly on the threaded shank 16', the trough surface 34 of the liner plates 11' will be outwardly displaced to contact the interior surface of the shell 10' and effect a peening action between complementary lifting elements 23'. Then, too, the peening action can be rendered more effective by disposing the liner plate apertures 14'-15' slightly offset from the center longitudinal line thereof to rockably peen the lifting element 24' relative to the adjacent lifting element 25' on the next liner plate 11'. Consequently, an effective liner plate 11' and integral lifting elements 23' in the form of complementary segments 24'-25' is provided to line the interior of the shell 10' without permitting any minute particles to find their way therebelow for undesirable packing against the interior surface of the shell 10'.

In a still further modified embodiment (Figures 5 to 7), the liner plates 11'' are substantially rectangular in configuration, and are curved transversely to conform with the curvature of the external shell 10''. Then, too, the lifting elements 23'' are specially constructed from the substantially rectangular plate 27'', having a curvature corresponding with that of the external shell 10'' and the liner plates 11'' for positioning therebetween. To this end, the lifting elements 23'' have a convex head 26'' of substantially greater curvature than its base plate 27'' for confronting relation therewith, it being welded or otherwise joined thereto along the inter-engaging surface thereof as at 36 and 37 to present laterally extending flanges 38 and 39 to receive the liner plates 11'' thereon.

The liner plates 11'' have their side edges 28'' and 29'' inclined outwardly and upwardly to substantially conform with the configuration of the convex lifting element head 26'' in the region of its joinder to the base plate 27'' thereof. Consequently, when the threaded fasteners 16'' are projected through the correspondingly shaped apertures 14'' and 15'' in the liner plates 11'' and drawn tightly by the threaded fastener nuts 21'', the curved substantially curved liner plates 11'' will retain the lifting elements 23'' in position to define a continuous and effective liner having intermediate lifting elements to render the grinding action more effective.

In a still further modified embodiment (Figure 8), the substantially flat liner plates 40 are rectangular in configuration similar to those described in connection with Figures 1 to 3, but the lifting elements are constructed from substantially elongated and rectangular plates 41 welded or otherwise joined to lifting bars 42 to present laterally offset flanges 43 and 44 serving to receive the liner plates 40 thereon and therebetween. In the present embodiment, the bars 42 have flat upper and lower surfaces with upwardly converging inclined sides 45 and 46 that project beyond the intermediate liner plates 40 having side edges 47 and 48 inclined oppositely thereto to serve as a complement thereof.

Apertures 49 are provided in the liner plates 40 to receive threaded fasteners 50 having correspondingly shaped heads 51 with non-turning nibs 52. The nibs 52 register with correspondingly inclined grooves 53 provided in the inclined wall of the liner plate apertures 49 to preclude relative rotation therebetween. Fastening nuts 54 engage the threaded fastening shank 50 with the shell 55 disposed therebetween. The fastener

nuts 54 serve to draw the liner plates 40 in by engaging contact with the side lateral flanges 43-44 of the lifting elements 42, thereby maintaining them in assembled relation to define a liner 40 combined with lifting elements 42 within the shell 55.

While the lifting elements 42 project upon the surface of the liner plates 40 in the embodiment which is described in Figure 8, in a still further modified embodiment shown in Figure 9, there is circumferential alignment between the upper surfaces of the lifting elements 42' and the arcuate surfaces of the liner plates 40' that are curved, in this instance, to correspond with the curvature of the shell 55'. It will be apparent, therefore, that the curved liner plates 40' together with the correspondingly sized lifting elements 42' define a continuous liner of smooth circumferential contour for anchored connection with the exterior shell 55' by means of the threaded fasteners described supra.

With the arrangement of parts above described, it will be apparent that a very effective, simple, inexpensive and readily replaceable liner plates and lifting elements are provided to define the interior surface of a grinding mill possessing novel features of shape, structure, arrangement, and grinding shell action. Various changes may be made in the embodiment of the invention herein specifically described without departing from or sacrificing any of the advantages of the invention or any features thereof, and nothing herein shall be construed as limitations upon the invention, its concept or structural embodiment as to the whole or any part thereof except as defined in the appended claims.

I claim:

1. A grinding mill comprising a cylindrical shell, comparatively thin liner plates disposed along the interior circumference of said shell, comparatively narrow lifting elements associated with said liner plates which are mounted thereon to yield in the direction of said shell, said liner plates being many times wider than said lifting elements and normally spaced from the interior of said shell by said lifting elements, and shell anchored fastener means connected to said comparatively thin liner plates and shell intermediate said lifting elements for yielding said liner plates toward and attachment thereof and said lifting elements to said shell responsive to tightening said fastener means.

2. A grinding mill comprising a cylindrical shell, comparatively thin liner plates disposed along the interior circumference of said shell, comparatively narrow sectional lifting elements detachably associated with said liner plates which are mounted thereon to yield in the direction of said shell, said liner plates being substantially wider than said lifting elements and normally spaced from the interior of said shell by said lifting elements, said liner plates being effectually yieldable by being substantially wider than said lifting elements, and shell anchored fastener means connected to said comparatively thin liner plates and shell intermediate said lifting elements for yielding said liner plates toward and attachment thereof and said lifting elements to said shell responsive to tightening said fastener means.

3. A grinding mill comprising a cylindrical

shell, comparatively thin rectangular liner plates disposed along the interior circumference of said shell, sectional lifting elements in the form of rails having side channels detachably associated with said liner plates, said liner plates being substantially wider than said lifting elements and normally spaced from the interior of said shell by said lifting elements by extending into the side channels thereof, and shell anchored fastener means connected to said comparatively thin liner plates and shell intermediate said lifting elements for yielding said liner plates toward and attachment thereof and said lifting elements to said shell responsive to tightening said fastener means.

4. A grinding mill comprising a cylindrical shell, comparatively thin flat rectangular liner plates disposed along the interior circumference of said shell, elongated rail form lifting elements having standard side channels detachably associated with said liner plates, said liner plates being substantially wider than said lifting elements and normally spaced from the interior of said shell by said lifting elements by extending into the side channels of said lifting elements, and shell anchored fastener means connected to said comparatively thin liner plates and shell intermediate said lifting elements for yielding said liner plates toward and attachment thereof and said lifting elements to said shell responsive to tightening said fastener means, said liner plates having sharp corner edge engagement with the side channels of said rails to preclude passage of the mill residue therethrough.

5. A grinding mill comprising a cylindrical shell, comparatively thin rectangular liner plates disposed along the interior circumference of said shell, lifting elements having inwardly protruding edges extending beyond said rectangular plates, said plates being substantially wider than said lifting elements and normally spaced from the interior of said shell, lateral flanges on said lifting elements for retaining engagement by said liner plates, said liner plates having sharp corner edge engagement with the side channels of said rails to preclude passage of the mill residue therethrough, and shell anchored fastener means connected to said liner plates and shell intermediate said lifting elements for yielding said liner plates toward and attachment thereof and said lifting elements to said shell responsive to tightening said fastener means.

6. A grinding mill comprising a cylindrical shell, comparatively thin rectangular liner plates disposed along the interior circumference of said shell, lifting elements having inwardly protruding edges extending in alignment with said rectangular plates, said plates being substantially wider than said lifting elements and normally spaced from the interior of said shell, lateral flanges on said lifting elements for retaining engagement by said liner plates, said liner plates having sharp corner edge engagement with the side channels of said rails to preclude passage of the mill residue therethrough, and shell anchored fastener means connected to said liner plates and shell intermediate said lifting elements for yielding said liner plates toward and attachment thereof and said lifting elements to said shell responsive to tightening said fastener means.

MAXWELL L. RAHNER.
